UNITED STATES PATENT OFFICE.

MATTHEW NICKELS, OF PHILADELPHIA, PENNSYLVANIA, ASSIGNOR OF ONE-HALF TO FRANK P. WAGNER, OF PHILADELPHIA, PENNSYLVANIA.

BURGLAR AND FIRE ALARM.

SPECIFICATION forming part of Letters Patent No. 757,490, dated April 19, 1904.

Application filed August 14, 1903. Serial No. 169,437. (No model.)

To all whom it may concern:

Be it known that I, MATTHEW NICKELS, a citizen of the United States, and a resident of the city of Philadelphia, State of Pennsylvania, have invented certain new and useful Improvements in Burglar and Fire Alarms, of which the following is a full, clear, and exact description, reference being had to the accompanying drawings, forming a part of this specification.

The invention to be hereinafter described relates to that class of combined burglar and fire alarms in which a gong or bell is struck by clock mechanism for giving the alarm, the mechanical construction being such that upon the release of a weight by the tripping of a catch or burning of the connection between the catch and the weight the clock mechanism is set free to sound the alarm.

With these general objects in view the invention consists of the several parts and combinations, as will be hereinafter fully described and then definitely pointed out in the claims.

In the drawings, Figure 1 is a view of the interior of a room or apartment, showing the general arrangement of my improved device as connected to the door and windows thereof. Fig. 2 is a detail perspective showing one form of catch as applied to detect the opening of a door or like structure. Fig. 3 is an enlarged elevation of the trip and alarm mechanism, the same being represented as inclosed in a suitable box or casing and the parts being shown in position for holding the alarm mechanism out of operation. Fig. 4 is a view similar to Fig. 3, but showing the parts in another position; and Fig. 5 is a sectional detail of the guideways.

Referring to the drawings, A represents a suitable casing of convenient size for holding the alarm and trip mechanisms to be described, said casing being preferably of ornamental character and provided with a door, as A'. Disposed within the casing A are the guideways B of any suitable number, depending upon the number of doors and windows to be guarded. The guideways B are preferably constructed as upright troughs, as shown, having in one side thereof a slot b, extending

from the top toward the bottom thereof, the lower ends of the troughs or guideways being closed, as by resting on a suitable block of wood or like material b', although, as will be evident, the particular manner of closing the lower ends of the guideways is immaterial.

Vertically movable within each guideway is a weight b², having an eyebolt or hook connection b³ with a series of flexible and combustible leaders b⁴, which are themselves provided at their ends with trip-hangers b⁵, (see Figs. 1 and 2,) adapted to engage pins b⁶ in suitable position with respect to the door or window to be guarded. In the case of a door the pin b⁶ may be driven in or secured to the door-framing, as shown in Fig. 2, or in case of window-shutters such pins b⁶ may be secured to one of the shutters, as shown in Fig. 1. In either event, however, it is desirable to provide means to insure the ready detachment of the trip-hangers from their pins b⁶ when the door or window-shutters are being opened, and such means in the present instance consists of a detaching or trip arm b⁷, which may be applied to the door, as shown in Fig. 2, or to one of the shutters, as in Fig. 1, the pins b⁶ in either event passing freely through suitable openings in the free end of the trip-arms, and the trip-hangers being then engaged over the pins. From the construction thus far described it will be evident, on reference to Figs. 1 and 2, that should the door or window-shutters be moved in an attempt to open any one of them the trip-arm b⁷ will push the trip-hanger from the pin and allow the weight b², connected with such trip-hanger, to drop to the bottom of its guideway B.

During the day, when the burglar-alarm is not needed, the trip-hangers may be applied to suitable hooks b⁸, secured in convenient position to the door or window framing to still hold the weights b² in their raised position in the guideways, so that should a fire occur the combustible leaders b⁴ will be burned, thus allowing the weights to fall and sound the alarm, as will presently appear.

Suitably mounted in the casing A is any usual form of alarm mechanism C, that illustrative of the invention being an ordinary

clock-alarm, which being of the well-known construction need not be specifically described. Such mechanism is provided with a bell *c*, which may be acted on by the hammer *c'* when 5 said hammer is free to move under the stress of the clock mechanism, as will be obvious.

Extending transversely across the slots *b* of the guides *B* is the trip-bar *D*, preferably in the form of a roller mounted in the bearings 10 *d d*, and below said trip-bar *D* is the trip- catch *E*, pivoted at *e* and provided with an end *e'*, adapted to engage a finger *c'* of the hammer *c'* and maintain said hammer out of operation, as shown in Fig. 3. Between the 15 pivot *e* and end *e'* the trip-catch is provided with an eye *e*, to which is connected a series of chains or other non-combustible flexible devices *f f*, having their other ends passed over the trip-bar *D* through the slots *b b* of the 20 guideways *B* and attached, respectively, to the weights *b² b²*. The chains or flexible connections *f f* are of such length that when the trip-hangers are hung to any of the pins *b⁶* or *b⁸* and the weights are in their elevated position, as 25 indicated in Fig. 3, the trip-catch *E* may assume the position indicated in said Fig. 3, with its free end *e'* in holding engagement with the finger *c'* of the hammer *c'*; but should any of the trip-hangers be detached from the pins *b⁶* 30 or should any of them be burned or severed the attached weight *b²* will fall to the bottom of its guideway *B*, as shown at the left of Fig. 4, thus pulling the chain *f* connected therewith over the trip-bar *D* and raising 35 the free end of the trip-catch from the finger *c'* of the hammer, thus freeing the hammer to the action of the clock mechanism and sounding the alarm.

It is evident, of course, that many details 40 may be changed or modified within the scope of my invention and that the guideways *B*, while preferably formed of cast or bent metal, may be differently constructed. By forming the slots *b* in the guideways it will be seen 45 that the chains may pass over the trip-bar *D*

into the guideways, where they connect with the weights, and that the weights are at all times free to move in the guideways while being protected thereby, and the stops at the lower end of the guideways serve to prevent 50 injury to the trip-catch or chain connection therewith when the weight falls. Of course it will be evident that the number of guideways and weights may be varied as circumstances require. 55

Having thus described my invention, what I claim, and desire to secure by Letters Patent, is—

1. A device of the type set forth, comprising a plurality of guideways, weights arranged 60 to slide in said guideways, a series of leaders attached to said weights, a trip-catch pivoted at one end in the casing, and extending across the said guideways, the opposite end of said trip-catch normally engaging the alarm, a 65 roller mounted in bearings and extending across the guideways, and means connected to said weights and to said trip-lever at an intermediate point thereof, and passing over the said roller for operating the said trip- 70 catch.

2. A device of the type set forth comprising a plurality of guideways, weights arranged to slide in said guideways, a series of leaders attached to said weights, a trip-catch pivoted 75 at one end in the casing, and extending across the said guideways, the opposite end of said trip-catch normally engaging the alarm, a roller mounted in bearings and extending across the said guideways, chains secured to 80 said weights and to said trip-catch at an intermediate point, and passing over the said roller.

In testimony whereof I have hereunto affixed my signature this 13th day of August, 85 A. D. 1903.

MATTHEW NICKELS.
